KNITTED GLOVE AND METHOD OF MAKING
THE SAMEMax Bialostok, Brooklyn, N. Y., assignor of one-
half to Joseph Bialostok, Lebanon, Pa.

Application August 21, 1937, Serial No. 160,221

4 Claims. (Cl. 2—169)

This invention relates to new and useful improvements in a knitted glove and a method for making same.

The invention has for an object the construction of a knitted glove which is characterized by the fact that a large percentage of the length of the seams in it have selvages or similar edges, in addition to stitches for sewing them together. Heretofore, it has been customary to construct 10 knitted gloves, the edge portions of which were merely sewed together without any finishing arrangement along them. Consequently, unraveling of the knitted material would take place, resulting in the opening of the seams.

15 The invention further contemplates the teaching of a method by which the glove may be manufactured in a particularly convenient and inexpensive manner.

More specifically, the invention proposes to 20 knit material from which the gloves are to be made in strips, and as the strip progresses through the knitting machine to form transverse openings in the strips arranged to divide off the sides and the areas between the fingers of the finished glove. It is proposed to so arrange the openings 25 that they have selvage edges. It is pointed out that when the areas of the knitted material are cut out to form the glove, the edges of the pieces will have selvage edges along the greater 30 part of their perimeter. It is thus possible to use these cutout pieces in the manufacture of the gloves merely by sewing the proper selvage edges together. A glove thus constructed is more durable, as the possibility of the edges unraveling 35 with consequent opening of the seams has been eliminated.

For further comprehension of the invention, and of the objects and advantages thereof, reference will be had to the following description 40 and accompanying drawings, and to the appended claims in which the various novel features of the invention are more particularly set forth.

In the accompanying drawings forming a material part of this disclosure:

45 Fig. 1 is an elevational view of a glove constructed according to this invention.

Fig. 2 is a sectional view taken on the line 2—2 of Fig. 1.

Fig. 3 is a fragmentary view of a portion of a 50 strip of knitted material constructed according to this invention and from which the glove is to be constructed.

Fig. 4 is a perspective view of another style of glove, constructed according to this invention, illustrated in folded condition, before the 55 glove is stitched.

Fig. 5 is a perspective view of a still further modification of this invention, showing a glove body before it is stitched.

60 In Figs. 1 and 2 a knitted glove 10 is illus-

trated which is more or less of conventional design and construction. It has a thumb portion 10^a and finger portions 10^b. It is formed by upper and lower layers which are sewn together by lines of stitches 11 along their edges. The 5 glove is turned inside out so that the seams are on the inside. The thumb 11^a is constructed and attached along the line 12, to the other portion of the glove body.

The glove shown in Figs. 1 and 2 distinguishes 10 from prior gloves in the fact that the edges 10' around most of the perimeter of the glove are selvage edges. Because of the selvage construction the possibility of the edges unraveling 15 is eliminated, and consequently one reason why the seams open, is avoided.

The method for constructing the glove may be clearly understood from Fig. 3. Fig. 3 illustrates a strip of knitted material 12 which is knitted with a plurality of openings 13, 14, 15, 20 16, etc. These openings are fashioned so that they surround an area 12^a of the strip of material 12, which area may be cut out to form the material of the glove. This area may be cut out at the rear, along the line 17. At the 25 front, that is the finger tip end of the glove, it may be cut out by cutting along the dot and dash lines 18, 19, 20, etc. When the piece 12^a is cut out it is intended that it be folded along the line 21 to form superimposed layers from 30 which the glove is constructed. Then it is proposed that the superimposed layers be sewn together along their edges, and finally that the glove be turned inside out.

The openings 13, 14, 15, 16, etc., are formed 35 with selvage edges. When the glove area 12^a is cut out the only portions not having selvage edges are the ends formed by the cut lines 11 and the cut lines 18, 19, 20, etc. As far as the cut line 17 is concerned, it is customary to provide trimming along this edge of the glove and therefore a selvage edge in this area is not necessary. In so far as the cut lines 18, 19, 20, etc., are concerned they represent 40 the finger tips. While the edges are not selvage edges and are subject to unraveling they are the areas at which little, if any stresses, occur 45 when the glove is worn. It is known that the greatest stresses in a glove are along the longitudinal lengths of the fingers because of the bending of one's fingers while the glove is worn.

With this instant method of construction the major portion of the sewn edges of the gloves are selvage edges. The method of construction is particularly inexpensive and requires merely 55 conventional operation of a knitting machine.

When the area 12^a is cut out and bent on the line 21, and is formed into a glove, it lacks a thumb. The thumb may be constructed separately and attached. This is advisable for manu- 60

factoring reasons generally known to the trade since that is the accepted method of constructing a glove.

The strip of knitted material 12 is knitted with the design of parallel colored lines 25 extending along the body and finger portions. These knitted parallel lines are adapted to simulate the conventional seams which extend along the body and finger portions of a finished glove. In this respect see Figs. 1 and 4. Stripes running in the length of the glove may be made in any width and in two or multitone colors.

It should also be noted that when the finger tips of the glove are formed, the parallel lines will be forced together at the points 25^a and so appear exactly like the conventional finger tip seams of a glove made from pieces sewed together. The glove at the fingers may be of different stitches than the body of the glove and may be shaped according to the shape of the hand.

Finished slits of any size may also be made in any part of the glove. Seams may also be provided inside or outside of the glove. The stripes are preferably on the outside of the glove and the palm of the hand is knitted in a solid color.

The glove may also be produced in solid individual colors for each finger or in any other color combinations.

In Fig. 4, the glove 13" is illustrated in folded condition, with the thumb portion 10^a stitched thereon but the edges of the glove left unstitched. In this form, the invention is shown with a strap 22 laced through slots 23 formed in the glove. This method of constructing gloves may be applied to any style and size of gloves.

The selvage edges may also be formed by ripping the knitted material.

The material is knitted flat by the machine and then it is finished to look like a tubular glove.

If the width of the machine is 100 inches, one can produce 9 pairs of gloves of ordinary size, along the width of the machine. Every 9 inches of cloth run down, brings out on the average, 8 pairs of gloves, or according to the size of glove wanted.

The main center seam may be finished in any part of the glove and left open to perform various styles.

Cuffs may also be added to the gloves.

The size of the glove is determined by the amount of needles used in the knitting machine.

The glove may also be in tubular form, by knitting on four bars instead of 2 bars. As illustrated in Fig. 5, the tubular fingers 30 are knitted in the glove by the knitting machine which also produces the two-tone stripes 31 around the fingers only, or around the fingers as well as the wrist on the tubular glove. The sides 32 may be left open by the machine or closed as desired.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A method for manufacturing a knitted glove consisting of knitting a strip of material with a plurality of transverse openings having selvage edges so that a pair of said openings outline the sides of an area which may be folded in half to form a front layer and a rear layer of the glove, and other of said openings outline the sides of areas which may form the fingers of the above, cutting the glove area out by cutting between said pair of openings and between the other openings, folding the area in half to superimpose the finger portions and the layers of the glove, and sewing the layers and finger portions closed.

2. A method for manufacturing a knitted glove consisting of knitting a strip of material with a plurality of transverse openings having selvage edges so that a pair of said openings outline the sides of an area which may be folded in half to form a front layer and a rear layer of the glove, and other of said openings outline the sides of areas which may form the fingers of the above, cutting the glove area out by cutting between said pair of openings and between the other openings, folding the area in half to superimpose the finger portions and the layers of the glove, and sewing the layers and finger portions closed, said openings with the selvage edges all being arranged substantially transversely of said strip.

3. A method for manufacturing a knitted glove consisting of knitting a strip of material with a plurality of transverse openings having selvage edges so that a pair of said openings outline the sides of an area which may be folded in half to form a front layer and a rear layer of the glove, and other of said openings outline the sides of areas which may form the fingers of the above, cutting the glove area out by cutting between said pair of openings and between the other openings, folding the area in half to superimpose the finger portions and the layers of the glove, and sewing the layers and finger portions closed, said openings with the selvage edges all being arranged substantially transversely of said strip, certain of said openings being arranged to extend substantially the entire width of the strip and defining the sides of the glove material.

4. A method for manufacturing a knitted glove consisting of knitting a strip of material with a plurality of transverse openings having selvage edges so that a pair of said openings outline the sides of an area which may be folded in half to form a front layer and a rear layer of the glove, and other of said openings outline the sides of areas which may form the fingers of the above, cutting the glove area out by cutting between said pair of openings and between the other openings, folding the area in half to superimpose the finger portions and the layers of the glove, and sewing the layers and finger portions closed, said openings with the selvage edges all being arranged substantially transversely of said strip, certain of said openings being arranged to extend substantially the entire width of the strip and defining the sides of the glove material, and the other of said openings being arranged along one edge of the strip and dividing the finger portions.
